UNITED STATES PATENT OFFICE.

CLARENCE U. DIXSON AND CHARLES L. HOWARD, OF COLUMBUS, OHIO.

WINDOW-SHADE SUPPORT.

No. 851,924.

Specification of Letters Patent.

Patented April 30, 1907.

Application filed July 13, 1906. Serial No. 326,029.

To all whom it may concern:

Be it known that we, CLARENCE U. DIXSON and CHARLES L. HOWARD, citizens of the United States, residing at Columbus, in the county of Franklin and State of Ohio, have invented certain new and useful Improvements in Window-Shade Supports, of which the following is a specification.

Our invention relates to adjustable supports for window shades and the objects of our invention are to provide an improved support of this class of superior construction and arrangement of parts; to so construct and arrange the same as to admit of its ready adjustment for the support of shades of different widths; to so construct my improved support as to permit of the shade roller being reversed when desired to cause the shade to roll either away from or toward the window, and to produce other improvements the details of which will be more fully pointed out hereinafter. These objects I accomplish in the manner illustrated in the accompanying drawings, wherein:

Figure 1 is a perspective view of one of our improved shade supports, and, Fig. 2 is an enlarged transverse section of the same showing for the sake of clearness in illustration, a portion of one of the supporting brackets broken away.

Similar numerals refer to similar parts throughout the several views.

Although but one of our improved shade supports will be described, it will be understood that one of these supports is adapted to be used on each side of a window frame.

In carrying out our invention, we employ a shade bracket support which comprises an oblong strip 1 of metal or other suitable material. This metal strip is provided throughout its length with a central projection 2 which forms on the rear side of the strip a central longitudinal channel 3. Formed in the outer face of the projection 2 is an elongated opening or slot 4, which at its outer end is enlarged as indicated at 4^a.

5 represents a shade supporting bracket, the body portion of which is preferably shaped substantially in the form of a human hand, the upturned fingers and thumb of which support and have rigidly connected therewith a shade roller supporting or bearing block 6 which as will be understood may be formed with the body 5 of the bracket, or

rigidly connected therewith. This supporting block has formed in its upper side a vertical recess 7 which is adapted to receive the usual squared or angular end pin of a spring actuated shade roller. Adjacent to the recess 7, the block 6 is also provided with a round hole or opening 8, the latter being adapted when the shade roller is reversed or turned end for end, to receive the round end bearing pin of the roller. The bracket 5 has formed or rigidly connected with its rear side 65 a rearwardly projecting threaded pin or bolt 9, which is adapted as shown in the drawing, to extend loosely through the slotted opening 4 of the projection 2 of the bracket support, the outer end of said threaded pin or bolt 70 having fixed thereon an enlarged head 10 which is of such size as to prevent the escape of the bolt or pin 9 through the main portion of the slot 4. This pin or bolt head, however, is adapted to be inserted through the enlargement 4^a of the slotted opening 4, after which the bolt is moved into the narrower or main portion of the slot, and the bolt head thus adapted, as shown, to bear against the inner face of the projection 2.

Upon the threaded portion of the bracket bolt or pin 9 and between the body of the bracket and the projecting portion 2 of the support 1, we provide a nut 11 which when turned as shown in Fig. 2, tightly against the 85 outer face of the projection 2, serves to clamp said projecting portion 2 of the support, firmly between the nut and bolt head and thereby rigidly support the bracket 5.

It will readily be understood that the supporting strips 1 are adapted to be secured to the inner surface of a window frame, one on each side of the window and that although the drawing herein shown, discloses the angular recess 7 as being on the inner portion of the block and the round opening 8 as on the outer side thereof, it will be understood that in the opposing block, the positions of this recess and opening are reversed. In order to bring the round opening in one shade supporting block opposite the square or angular opening of the opposing block and thus provide for the reception of the usual squared and round end pins of a shade roller.

It will be obvious that shade supporting 105 brackets such as herein described may be readily adjusted with reference to the distance between them by loosening the nut 11

2
of either or both of the brackets, moving the bolt or pin projection 9 to a new position in the slot 4 and again tightening the nut against the projection 2.

5 Window shades are ordinarily so supported in the brackets as to provide for the winding of the shade on to the roller from the rear side of the latter, but by providing the shade roller supporting blocks 6 with both the 10 round and square openings 7 and 8, it will readily be understood that the shade roller may be reversed or turned end for end to admit of the shade being rolled on to the roller from the outer side of the latter.

15 From the foregoing description, it will be seen that simple and efficient means are herein provided for accomplishing the objects of the invention, but while the elements shown and described are well adapted to serve the 20 purposes for which they are intended, it is to be understood that the invention is not limited to the precise construction set forth, but includes within its purview such changes as 25 may be made within the scope of the appended claims.

What we claim, is:

In a device of the character described, the combination with a supporting member having flanges adapted to be secured to a window frame and having a forwardly extending offset portion in the front wall of which a key-hole slot is formed, a shade roller supporting bracket carrying a rearwardly extending headed member which is adapted to pass through the enlarged portion of the key-hole slot and to engage behind the front walls of the offset portion, and a binding nut threaded upon said headed member between the shade roller bracket and the front wall of the offset portion of the supporting member, said binding member being adapted to clamp said wall between itself and the head of the headed member.

In testimony whereof we affix our signatures in presence of two witnesses.

CLARENCE U. DIXSON.
CHARLES L. HOWARD.
